UNITED STATES PATENT OFFICE.

CHARLES L. RAYFIELD, OF CHICAGO, ILLINOIS, ASSIGNOR TO FINDEISEN & KROPP MANUFACTURING COMPANY, OF CHICAGO, ILLINOIS, A CORPORATION OF ILLINOIS.

CARBURETER.

1,354,686.

Specification of Letters Patent.

Patented Oct. 5, 1920.

Application filed September 15, 1916. Serial No. 120,382.

To all whom it may concern:

Be it known that I, CHARLES L. RAYFIELD, a citizen of the United States, and a resident of the city of Chicago, in the county of Cook and State of Illinois, have invented certain new and useful Improvements in Carbureters; and I do hereby declare that the following is a full, clear, and exact description of the same, reference being had to the accompanying drawings, and to the numerals of reference marked thereon, which form a part of this specification.

This invention relates to that type of carbureters wherein a fuel dash pot chamber is provided on the carbureter with a piston therein movable by the air inlet valve of the carbureter to steady the movement of the air inlet valve and further serving to provide a means of introduction of fuel from the dash pot chamber to carburet the air flowing past the air inlet valve to intermix with the air and fuel entering other parts of the carbureter as well as from a primary nozzle therein.

It is an object therefore of this invention to construct a carbureter wherein the dash pot chamber thereof, communicating with the float feed chamber of the carbureter, is provided with a piston actuatable by the automatic air inlet valve of the carbureter serving to effect a passage of fuel upwardly through the stem of the air valve and piston for distribution at the periphery of the air valve into the current of air flowing there past.

It is also an object of this invention to construct a carbureter wherein an automatic air valve operating to move a piston in a fuel dash pot chamber is provided with a fixed metering pin provided on the interior of the stem so disposed that the continued movement of the air valve piston and stem serves to increase the area of opening past said metering pin for flow of fuel upwardly for distribution at the periphery of the air valve into the current of entering air.

It is also an object of this invention to construct a carbureter wherein an automatic air inlet valve is provided having fuel ori-

50 fices disposed in the periphery of the air valve to introduce fuel into the entering air at the point of greatest velocity thereof to insure intermingling thereof with the air flowing past said air valve.

55 It is furthermore an object of this inven-

tion to provide an improved air valve and auxiliary fuel supply means for a carbureter whereby fuel, under sudden draft through the carbureter, is forced under pressure upwardly for distribution through and at the periphery of the air valve at the point of greatest velocity of the entering air and in quantities dependent upon the extent of opening of the air valve.

It is finally an object of this invention to construct an improved type of auxiliary air inlet and secondary fuel supply means for a carbureter, wherein a fixed metering pin is utilized in connection with a movable seat or nozzle mechanism operated by the auxiliary air valve of the carbureter.

The invention (in a preferred form) is illustrated in the drawings and hereinafter more fully described.

In the drawings:

Figure 1 is an elevation of one side of a carbureter embodying the principles of my invention.

Fig. 2 is an elevation of the other side thereof.

Fig. 3 is a central vertical section taken through the carbureter with parts in elevation.

Fig. 4 is a central vertical section taken through one end of the carbureter with parts in another position of adjustment from that shown in Fig. 3.

Fig. 5 is a detail section taken on line 5—5 of Fig. 4.

Fig. 6 is a detail section taken on line 6—6 of Fig. 4.

Fig. 7 is a bottom plan view of the piston in the dash pot chamber.

As shown in the drawings:

The carbureter casing embraces a float chamber 1, having formed integrally therewith a mixing chamber 2, and said float chamber 1, is provided with an extension chamber 3, communicating with the mixing chamber 2, and having a normally open air port 5, therein, and with a fuel nozzle 6, threaded into the partition wall between the fuel chamber extension 3, and the air passage 4, for flow of fuel thereinto. A float 7, is mounted within the float chamber 1, operating in a usual manner to control the inlet of fuel to the float chamber, the supply line for the carbureter being denoted by the reference numeral 8. A throttle valve 9, is provided to control the outlet from the mix-

75

ing chamber 2, and is mounted upon a shaft 10, on which a lever 11, on the exterior of the carbureter, is connected for operating the throttle valve. A needle valve 12, is provided to control the flow through the nozzle 6, and is adapted to be elevated by a finger 13, secured in a shaft 14, journaled horizontally of the carbureter casing and provided on its outer end with a crank 15, one end of which is disposed adjacent the throttle valve shaft 10, in position to be contacted by a cam 16, thereon whereby the crank is operated to rotate the shaft 14, and adjust the needle valve 12. However, since this interconnection between the throttle valve 9, and the needle valve 12, is a well known mechanism in carbureters, which I have invented and patented heretofore, a detailed description thereof is not entered into, since this forms no part of the present invention.

Secured upon the main carbureter casing adapted to afford an inlet in the side of the mixing chamber 2, is a casing 17, having an air inlet passage 18, therethrough and a dash pot chamber 19, formed on the lower end thereof closed by a threaded closure plug 20. An inlet passage 21, for fuel is provided in one side wall of the dash pot chamber 19, and a pipe 22, is connected into said passage 21, and leads to the float chamber extension 3, of the carbureter.

Threaded adjustably into the upper open end of the casing 17, is an annular valve seat member 23, and an upwardly directed tubular extension 24, is provided on the top wall of the dash pot chamber 19, communicating with the interior of the dash pot chamber through which a tubular valve stem 25, slidably extends with a valve 26, secured upon the upper end thereof adapted to seat against said annular valve seat. A piston 27, having apertures 28, therethrough, is secured upon the lower end of the stem 25, and is movable within the dash pot chamber 19, and a flat valve or disk 29, is mounted on the other side of said piston adapted during downward movement of the piston to close the passages 28, therethrough and to open during upward movement of the piston to permit passage of the fuel from the upper portion of the dash pot chamber to the lower portion thereof to permit a comparatively quick return of the piston to normal.

Rigidly secured by threaded engagement with the closure 20, of the dash pot chamber 19, and projecting upwardly, is a long tapered metering pin 30, which extends into the tubular valve stem 25, and secured within the lower end of said stem, is a short sleeve or cylinder 31, which coacts with the fixed metering pin to vary the area of the annular opening through said sleeve or cylinder dependent upon its position of adjustment with respect to the metering pin which

is determined by the position of the air valve 26, and the piston 27, in the dash pot chamber. The upper end of the tubular valve stem 25, is provided with apertures which communicate with passages 32, formed horizontally through the lower portion of the air valve 26.

A conical deflecting shield or cover 33, secured upon the upper end of the air valve 26, extends downwardly and is spaced away from the ends of the passages 32, opening through the surface of the valve to deflect the air therefrom and induce an aspiration effect through said passages to augment the flow of fuel therethrough received upwardly through the tubular stem from the dash pot chamber. Secured beneath the air valve 26, is a tubular member 34, having integral therewith a long yoke lever 35, which extends inwardly through the air inlet passage 18, into the mixing chamber 2, and is connected to one end of a link 36, the opposite end of the link being pivotally connected with a butterfly valve 37, to control the opening in the lower end of the mixing chamber 2. A coiled compression spring 38, is disposed around the stem of the valve 26, bearing upwardly beneath said valve to normally thrust the same into closed position.

The operation is as follows: The air valve 26, in the position shown in Fig. 3, is at normal or in closed position, and the area of passage around the stationary metering pin 30, through the sleeve or cylinder 31, for fuel from the dash pot chamber 19, into the tubular valve stem 25, is at a minimum. Due to the fact that no flow of air takes place past the outer end of the passages 32, and due also to the fact that the same are disposed considerably above the normal level of fuel in the float chamber, no flow of fuel is discharged therethrough. When the throttle valve 9, is moved toward open position, a suction draft is exerted through the carbureter which on becoming sufficient to overcome the stress of the spring 38, opens the air valve 26, thus moving the sleeve or cylinder 31, downwardly around the tapered stationary metering pin 30, to increase the area of passage for entrance of fuel upwardly through the tubular valve stem 25. With sufficient depression of the valve 26, and sufficient flow of air around the periphery of said valve into the air inlet passage 18, of the carbureter, fuel will be drawn upwardly through the tubular stem 25, and discharged through the passages 32, of the air valve into the rapidly moving current of air. The air valve 26, as it moves downwardly causes the piston to move downwardly within the dash pot 19, opening the passage around the stationary metering pin 30, and causing a flow of fuel under pressure from beneath this piston to take place upwardly through the tubular stem 180

25, and sprayed outwardly through the passages 32, provided in the air valve 26. A flat or check valve 29, provided on the under side of the piston 27, serves to close the passages 28, through said piston during downward movement of the piston but drops downwardly to permit a flow of fluid downwardly therethrough as the piston moves upwardly in the dash pot, so that passage of 10 fuel may take place from the upper portion of the dash pot to the lower portion thereof beneath the piston to permit a quick return of the piston to normal.

I am aware that various details of construction may be varied through a wide range without departing from the principles of this invention, and I therefore do not purpose limiting the patent granted otherwise than necessitated by the prior art.

20 I claim as my invention:

1. In a carbureter of the class described, an automatic air valve, a dash pot chamber, a piston therein, operated by said air valve, a tubular valve stem affording connections 25 between said air valve and piston, a stationary metering pin mounted within said tubular valve stem whereby the quantity of flow from the dash pot chamber to the piston is varied according to the adjustment of the 30 stem on the metering pin, passages formed through the air valve communicating with the tubular stem, whereby the fuel from the dash pot chamber, may be sprayed into the air entering the carbureter and means deflecting the air from the fuel passages.

2. In a carbureter of the class described, a float feed chamber, an automatic air valve, a dash pot chamber, communication between said float feed chamber and the upper end of 40 said dash pot chamber, a piston in said dash pot chamber, a tubular valve stem secured thereto and communicating centrally therethrough, a fixed metering pin mounted in said dash pot chamber and extending upwardly within said tubular valve stem, a 45 check valve associated with said piston to resist the downward movement of the piston, whereby the fuel is compressed therebeneath and forced upwardly through said valve stem, and passages through said air valve to receive the fuel from the tubular valve stem, to carburet the air entering the carbureter.

3. A carbureter comprising a float chamber, a fuel nozzle therefor, a dash pot chamber communicating with the float chamber, an automatic air valve having passages above its seat communicating with the dash pot chamber, a piston movable with the air valve to pump fuel through the passages, a 55 stationary metering pin for regulating the amount of fuel pumped through said passages and a deflector for deflecting the air from the passages to induce an aspiration effect through said passages.

60 4. In a carbureter a dash pot chamber for

containing fuel, a piston therein, an air valve having radially opening apertures, a hollow stem connecting the air valve and piston and affording communication between the radial apertures and the dash pot 70 below the piston, a tapered metering pin rigidly mounted in the dash pot and extending upwardly into the stem, a sleeve secured in the stem, coacting with the metering pin to regulate the flow of fuel through the stem 75 and a spring for automatically forcing the air valve closed.

5. A carbureter comprising a float feed chamber, a dash pot chamber communicating therewith, a piston in the dash pot 80 chamber having openings therethrough, an air valve provided with fuel passage therethrough, a hollow stem connecting the air valve and piston and affording communication between the dash pot and fuel passages, 85 a metering pin extending into the stem, means in the stem coacting with the metering pin to vary the quantity of fuel delivered to the fuel passages, a disk secured to the piston adapted to close over the holes 90 therein as the piston moves downwardly to thereby force the fuel up the stem and adapted to uncover the holes when the piston moves oppositely to permit the fuel passing therethrough for a quick return of the 95 piston and a spring for normally holding the air valve closed.

6. A carbureter comprising a float chamber, a dash pot chamber communicating therewith, an air inlet, a valve for closing 100 the same provided with laterally opening passages, a stem secured to the valve and communicating with the passages and the dash pot, a piston movable with the stem 105 adapted to pump fuel therethrough, a metering pin projecting into the stem, a spring for normally holding the valve seated and a deflector secured to the valve for deflecting the air from the discharge ends of the passages.

7. In a carbureter the combination with a casing having a mixing chamber and float feed means for controlling the supply of fuel to the carbureter, of an automatic air valve controlling the admission of air to the mixing chamber, a fuel pump operated by the air valve and having an outlet for supplying fuel to the mixing chamber through which said outlet fuel is forced by the pump when the air valve is opened, and a manually adjustable metering pin for said outlet for regulating the discharge therefrom proportionately to the opening of the air valve.

8. In a carbureter the combination of a 125 casing having a mixing chamber and float feed means for controlling the supply of fuel to the carbureter, of an automatic air valve for controlling the admission of air to the mixing chamber, a fuel pump oper- 130

ated by the air valve and having an outlet for supplying fuel to the mixing chamber, through which said outlet fuel is forced by the pump when the air valve is opened, 5 and a stationary metering pin for said outlet for regulating the discharge therefrom proportionately to the opening of the air valve.

9. In a carbureter, the combination with 10 a casing having a mixing chamber and float feed means for controlling the supply of fuel to the carbureter, of an automatic air valve for controlling the admission of air to the mixing chamber, a fuel pump having 15 a hollow stem connected with the air valve and provided with outlets from the hollow stem through which fuel is forced by the pump when the air valve is opened, and a metering pin projecting into the hollow 20 stem for regulating the discharge from said outlet proportionately to the opening of the air valve.

10. In a carbureter the combination with 25 a casing having a mixing chamber and a float feed chamber for controlling the sup-

ply of fuel to the carbureter, of an automatic air valve for controlling the admission of air to the mixing chamber, a piston operable with the air valve and having an inclosing cylinder with an outlet at one side 30 of the piston through which fuel is forced by the piston to the mixing chamber when the valve is opened, a duct for supplying fuel from the float feed chamber to the cylinder at the other side of the piston, and 35 a passage through the piston having a valve adapted to close when the piston is operated to force fuel through said outlet from the cylinder and adapted to open when the piston operates in the reverse direction and admit fuel through the passage of the piston 40 to fill the outlet side of the cylinder.

In testimony whereof I have hereunto subscribed my name in the presence of two subscribing witnesses.

CHARLES L. RAYFIELD.
